United States Patent Office.

HENRY S. HUBBELL AND ALFRED S. HUBBELL, OF BUFFALO, NEW YORK.

Design No. 2,839, dated November 26, 1867.

DESIGN FOR STOVE-PLATES.

The Schedule referred to in these Letters Patent and making part of the same.

TO ALL WHOM IT MAY CONCERN:

Be it known that we, HENRY S. HUBBELL and ALFRED S. HUBBELL, of the city of Buffalo, county of Erie, and State of New York, have invented or produced a new and original Design for a Heating-Stove, called the Dictator; and we do hereby declare that the following is a full and exact description of the same, reference being had to the accompanying photograph, and to the letters of reference marked thereon.

The photograph represents the side and front end and doors of stove.

Letter A is the side. Letter B is the front end and doors.

What we claim as our invention, and desire to secure by Letters Patent, is—

The ornamental design for side of stove, marked A, and the ornamental design for front end and front doors, marked B, in the accompanying photograph.

HENRY S. HUBBELL,
ALFRED S. HUBBELL.
